TUYÈRE BLOCK

William V. McAllister and Leslie G. Korte, Detroit, Mich., assignors to Riley Stoker Corporation, Worcester, Mass., a corporation of Massachusetts

Application January 30, 1935, Serial No. 4,133

5 Claims. (Cl. 110—44)

This invention relates to tuyère blocks, and more particularly to tuyère blocks for use in automatic stokers to support the fuel and distribute air thereto for combustion.

5 In automatic stokers of the underfeed type, it is customary to utilize rows of tuyère blocks located between the stoker retorts, the blocks in each row being arranged in an overlapping or step-like formation to provide a tuyère structure 10 which slopes downwardly toward the rear of the furnace. In such a tuyère structure, the rear or nose portion of each tuyère block is exposed to contact with the fuel bed, whereas the front or main body portion of the block is protected 15 by the block thereabove. Even with the most careful operation, groups of tuyère blocks sometimes become overheated, perhaps as a result of thin spots in the fuel bed, and it becomes necessary to replace the damaged blocks at considerable expense. It is of course necessary to shut 20 down the furnace before such replacement can be made.

It has been recognized heretofore that tuyère block replacement is a serious problem in stoker 25 operation, and various remedies have been suggested. For example, it has been proposed to construct the heat exposed portion of each block of a separate piece which can be renewed independently of the body of the block, but it is found 30 that these separate pieces are destroyed by the heat much more rapidly than blocks of the usual construction. It has also been proposed to utilize protecting caps of refractory material for the heat exposed portions of the blocks, but such 35 caps are expensive and they cannot satisfactorily withstand the combined effect of the heat, the chemical action of the ash from the fuel, and the abrasion of the fuel bed. While heat-resisting 40 metals have been developed, tuyère blocks constructed from them are so expensive as to prevent any economic saving by their use.

It is accordingly the main object of the invention to overcome these difficulties and to provide 45 a tuyère block which will be relatively inexpensive to manufacture and which will have a useful life of service comparable to that obtainable with tuyère blocks constructed entirely of heat resisting metal.

50 With this and other objects in view, as will be apparent to those skilled in the art, the invention resides in the combination of parts set forth in the specification and covered by the claims appended hereto.

55 Referring to the drawing illustrating one em-

bodiment of the invention, and in which like reference numerals indicate like parts,

Fig. 1 is a perspective view of a tuyère block for an underfeed stoker;

Fig. 2 is an elevation of a series of tuyère blocks 5 assembled on a stoker;

Fig. 3 is a top plan view of a mold for use in casting a tuyère block; and

Fig. 4 is an elevation of the mold ready for the 10 pouring operation, shown in partial section on the line 4—4 of Fig. 3.

The tuyère block illustrated in Fig. 1 is of the general type disclosed in the patent to Armour No. 1,896,569, granted February 7, 1933, and comprises a thin elongated flat substantially horizontal plate or web 10 having spaced ribs 11 on its lower face forming air channels. A rectangular opening 12 is provided in the front portion of the web to reduce the resistance to the flow of air through the blocks when assembled. Two flanges 14 extend downwardly from opposite sides of the block at the front end thereof, the lower edges of these flanges sloping downwardly and rearwardly. A bolt hole 15 is provided in the web 10 in the rear of the opening 12. 15

The tuyère blocks are mounted in a step-like formation upon a downwardly and rearwardly sloping stoker side-bar or retort side 17, as shown in Fig. 2, with the flanges 14 engaging the upper surface of the side-bar. It will be understood that the side-bar is of hollow construction, 20 as is customary, so that air may flow upwardly therethrough and escape to the fuel bed through the channels between the ribs 11. 25

It will be noted from Fig. 2 that only a comparatively small nose portion 19 at the rear end of each tuyère block is exposed to the fuel bed thereabove, and that the main body portion of each tuyère block is protected by the next higher block in the series. With blocks as heretofore constructed, these nose portions have frequently become so damaged by the conditions encountered in service as to require replacement of the blocks at considerable expense. Attempts to solve the problem by providing separately replaceable nose 30 portions of expensive heat-resisting metals have proven unsuccessful, and in our opinion this is due to the lack of sufficient heat transmission from the nose portion to the main body of the block. 35

In order to overcome these difficulties, we construct the entire main body of the tuyère block of a comparatively cheap metal, such as ordinary cast iron, and we form the entire nose portion 19 40 of a suitable heat-resisting metal which is so 45

joined to the main body as to ensure rapid heat transmission thereto. In the preferred embodiment the metal of the nose portion is integrally united with the metal of the body portion, 5 and the junction between the two metals extends along a plane which slopes downwardly and rearwardly with respect to the web 10 of the block, as indicated by the dotted lines in Figs. 1 and 2. The integral union of the two metals over the 10 substantial area represented by this inclined plane ensures the transmission of heat at a very rapid rate from the nose portion of the block to the comparatively cool main body portion, thus maintaining the nose portion at a temperature 15 no higher than would be found in a homogeneous block under identical operating conditions. At the same time the inherent characteristics of the metal forming the nose portion enable it to withstand the operating conditions successfully. It 20 will be noted that by sloping the junction plane downwardly toward the rear, we are able to obtain a relatively large area for the upper surface of the heat-resisting metal without requiring an excessive amount of this metal. In this way we 25 use the costly material to the best advantage. It will be clear from Figs. 1 and 2 that the main body portion of the block is wedge shaped in longitudinal vertical section at its rear end, with the acute angle of the wedge at the bottom, and 30 the nose portion 19 is wedge shaped in longitudinal vertical section at its forward end with the acute angle of the wedge at the top, the sloping surfaces of the two wedge shaped portions being integrally united.

35 By the term "heat-resisting metal" we do not necessarily mean a metal having a high melting point. In fact the metals which we consider best suited for our purpose probably melt at substantially the same temperature as ordinary cast iron. It is unusual for even the nose portion of 40 a stoker tuyère block to reach the melting point. The in-flowing air has sufficient cooling effect to prevent this under any normal operating conditions. The damage to tuyère blocks as heretofore constructed is we believe caused primarily by 45 growth and oxidation. Growth of cast iron is a gradual permanent enlargement under the influence of heat, and particularly alternate heating and cooling. It greatly distorts and weakens 50 the metal, and produces internal stresses which result in cracking and rapid disintegration of the block. Oxidation is of course a chemical combination of the metal with oxygen, a reaction which is greatly accelerated at high temperatures, causing 55 scaling and wasting away of the metal. We are therefore primarily interested in a material which will remain comparatively free from growth and oxidation when exposed to high temperatures in an oxidizing atmosphere. It is a material of this nature to which we refer when 60 we use the term "heat-resisting metal."

Various heat-resisting metals may be utilized for our purposes. One suitable material is an alloyed cast iron, austenitic in structure, and having an analysis as follows:

	Per cent
Total carbon-----	2.75- 3.10
Silicon-----	1.25- 2.00
Nickel -----	12.00-15.00
Chromium-----	1.50- 5.00
Manganese-----	.80- 1.50
Copper-----	5.00- 7.00

While an alloy of this type may be produced in a cupola, we much prefer to utilize an electric furnace, as it makes possible better control of

the metal, a more uniform composition, and a higher pouring temperature.

In the manufacture of our improved tuyère block, we prepare a sand mold 21 having a mold cavity 22 of a shape corresponding to the desired shape of the tuyère block. This mold may be produced in the usual manner by means of a snap-flask, which is removed after completion of the mold and a supporting metal jacket 23 substituted therefor. The mold 21 is preferably provided with two pouring basins 25 and 26, which communicate by means of gates 27 and 28 respectively with the cavity 22. Gate 27 leads to the portion of the cavity which corresponds to the main body of the tuyère block, and gate 28 leads to the portion of the cavity which corresponds to the nose portion of the block.

After completion of the mold it is tipped to a predetermined angle with the horizontal, with gate 28 higher than gate 27, and in order that the castings may be uniform we preferably mount each mold upon a wedge-shaped block 30 having an inclined upper surface, as shown in Fig. 4. With the mold in this position a suitable molten metal, such as ordinary cupola iron, is poured into the basin 25 and enters the cavity 22 through the gate 27. The pouring is continued until the metal reaches the level indicated by the broken line 32, at which time the metal will be about to overflow from the pouring basin 25. After an interval of time sufficient for the iron to cool slightly, the molten alloyed iron is poured at a comparatively high temperature into the basin 26 and flows through the gate 28 into the upper portion of the cavity 22 to form the nose of the tuyère block. If the time interval between the two pourings is correct, the two metals will not mix to any appreciable extent, and yet they will be fused together and integrally united along the junction plane. The proper interval for any particular design of tuyère block can be easily determined by trial. With the tuyère block illustrated, and a web $\frac{3}{8}$ of an inch in thickness, we have found that a time interval of approximately thirty seconds is satisfactory.

Because of the comparatively small quantity of alloyed iron required for the nose portion 19, the cost of the finished tuyère block will not greatly exceed the cost of the usual block constructed entirely of ordinary cast iron, and yet 50 our improved block will have a useful life far exceeding that heretofore obtainable. This results from the ability of the metal of the nose portion to resist growth and oxidation at fairly high temperatures, and the effect of the integral bond between the two metals in transferring heat at a rapid rate along the block, thus preventing the nose portion from reaching too high a temperature. It is by combining these two factors that we are able to obtain long life at a comparatively 60 low cost.

Having thus described our invention, what we claim as new and desire to secure by Letters Patent is:

1. A tuyère block comprising a front horizontally extending main body portion which is wedge shaped in longitudinal vertical section at its rear end and formed of a comparatively inexpensive metal, and a rear horizontally extending fuel supporting portion which is wedge shaped in 70 longitudinal vertical section at its forward end and formed of a heat-resisting metal, the two portions of the block being integrally united throughout a junction plane which is inclined from the horizontal.

2. A tuyère block comprising a front horizontally extending main body portion formed of a comparatively inexpensive metal and wedge shaped at its rear end with the acute angle of the wedge at the bottom, and a rear horizontally extending fuel supporting portion formed of a heat-resisting metal and wedge shaped at its forward end with the acute angle of the wedge at the top, the sloping surfaces of the two portions being integrally united to ensure rapid transmission of heat between them.

3. A tuyère structure for a stoker comprising a series of tuyère blocks piled in a downwardly and rearwardly sloping step-like formation with the rear end of each block exposed, the forward portion of each block being formed of a comparatively inexpensive metal and the rear portion being formed of a heat-resisting metal, the two portions of each block being integrally united throughout a junction plane which extends from the upper surface of the block to the lower surface thereof.

4. A tuyère structure for a stoker comprising a series of tuyère blocks piled in a downwardly and rearwardly sloping step-like formation with the rear end of each block exposed, the rear

portion of each block being formed of a heat-resisting metal and wedge shaped in longitudinal vertical section at its forward end, and the forward portion of each block being formed of a comparatively inexpensive metal and wedge shaped in longitudinal vertical section at its rear end, the two portions of each block being integrally united throughout a junction plane which is inclined from the horizontal.

5. A tuyère structure for a stoker comprising a series of tuyère blocks piled in a downwardly and rearwardly sloping step-like formation with the rear end of each block exposed, the rear portion of each block being formed of a heat-resisting metal and wedge shaped in longitudinal vertical section at its forward end with the acute angle of the wedge at the top, and the forward portion of each block being formed of a comparatively inexpensive metal and wedge shaped in longitudinal vertical section at its rear end with the acute angle of the wedge at the bottom, the two portions of each block being integrally united throughout a junction plane which is inclined downwardly and rearwardly.
